(57) **CLAIM**

The ornamental design for a leveling ramp assembly as shown and described.

DESCRIPTION

FIG. 1 is a front perspective view of a leveling ramp assembly showing our new design;

FIG. 2 is a rear perspective view of the leveling ramp assembly of FIG. 1;

FIG. 3 is a front elevational view of the leveling ramp assembly of FIGS. 1 and 2;

FIG. 4 is a left side elevational view of the leveling ramp assembly of FIGS. 1-3;

FIG. 5 is a rear elevational view of the leveling ramp assembly of FIGS. 1-4;

FIG. 6 is a right side elevational view of the leveling ramp assembly of FIGS. 1-5;

FIG. 7 is a top plan view of the leveling ramp assembly of FIGS. 1-6; and,

FIG. 8 is a bottom plan view of the leveling ramp assembly of FIGS. 1-7.

The broken lines are included for the purpose of illustrating portions of the leveling ramp assembly that form no part of the claimed design.

1 Claim, 8 Drawing Sheets
